UNITED STATES PATENT OFFICE

LOUIS SCHER, OF CLEVELAND, OHIO

TICKET-DELIVERY MECHANISM

Application filed June 25, 1927. Serial No. 201,525.

My invention relates to improvements in ticket delivery mechanism, and has for its object the provision of co-operating means for accurately delivering and registering one or a plurality of tickets of the same or of different character; such means to be of extreme simplicity, accuracy of operation, and with minimum liability to impairment by wear, or to get out of order.

10 There may be associated with my improved mechanism any desired ticket printing, marking, canceling, or checking means, but these form no part of the instant invention, which will here be described as an associated 15 group of delivery sections capable of key-controlled issue and detachment of one or more ticket strips, according to the varying requirements at a ticket booth.

It may be explained in a preliminary way 20 that the ticket delivery sections are identical in construction and preferably those of a group are operated by a common motor device which is constantly driven during the ticket selling periods, so that any section 25 is potentially ready for the delivery of its class of tickets from previously printed and prepared strips.

Each section is equipped with a plurality 30 of keys which control in common a master-key that is adapted to set the delivery mechanism into operation and to check it after one complete cycle. The number of coupons of any instantly delivered ticket strip is regulated by the particular operator's key depressed in actuating the master-key. The 35 delivery mechanism, per se, is operated upon the restoring movement of its parts to the initial position thereof, while a counter is provided to register the total sales.

40 The features of my improvement may best be explained, together with the operation of the mechanism and the advantages thereof by making reference to the accompanying drawings, wherein:

45 Figure 1 is a view of one section of my improved ticket issuing mechanism shown in end-elevation, partially broken away and in dotted lines indicating the principal members in their inoperative or starting position.

50 Fig. 2 is a rear view thereof, partially

broken away to illustrate the mechanism of one section,

Fig. 3 is a similar view thereof from the front,

Fig. 4 is a plan view of two sections,

Fig. 5 is an enlarged schematic view of the principal members of one section in side elevation, whereby the operation may more readily be explained,

Fig. 6 is a fragmentary view of the key-operating and releasing mechanism,

Fig. 7 is a fragmentary section on line 7—7, Fig. 6,

Fig. 8 is a side elevation of the ticket wheel and actuating ratchet mechanism,

Fig. 9 is a fragment showing the ticket wheel shaft with its coacting members,

Fig. 10 is a fragmentary view of the ticket cutting means,

Fig. 11 is a detail to illustrate the starting means, and

Fig. 12 is a portion of the perforated ticket strip.

Throughout the several figures of the drawings I have employed the same character of reference to indicate similar parts.

My improved ticket delivery mechanism preferably is constructed with a plurality of identical related sections primarily designed for the issue of different classes of tickets; each section being equipped to issue and to keep total count of one or a plurality of the particular class of tickets, up to any desired or predetermined number. The more common requirement, however, is for a mechanism which will rapidly deliver any number of tickets up to and including five such tickets or coupons, and my improved mechanism is herein set forth with this preferred capacity.

Referring first to Figures 4 and 5, it will be seen that a plurality of identical ticket delivery sections are disposed in alinement (two of which are shown) for the convenient operation of the ticket seller or, sellers, and for the purpose of issuing different classes of tickets that are automatically withdrawn and severed from individual coils of ticket strips, respectively. Thus, tickets for adults and for children may be issued by the two sections, respectively, indicated in Fig. 4, and

in strips containing from one to five such ticket coupons. The totals respectively will be registered upon the counting devices as the sales are made. The lengths of such strips are governed by the depression of the numbered keys corresponding with the number of ticket coupons required from time to time for each sale.

The gear a upon the left is driven by a pinion a' and motor a'' , as shown in Fig. 2, or by any suitable motor device. Interposed gearing a^3 serves continuously to rotate shaft b^4 extending through all of the associated sections of the group, whether one or 15 a dozen such sections, while gearing a^4 rotates the respective shafts b of each section in counter-clockwise direction as long as the motor is connected in circuit.

The co-operation of the sections, resulting 20 in a material saving of time in the issue of tickets, may be explained with respect to the two sections shown, assuming that they respectively are provided with adults' and children's tickets, which commonly are called 25 for in variable groups at the majority of ticket-selling windows. Thus, to illustrate, two adults' tickets and three children's tickets will be delivered simultaneously when the operator presses key "2" upon the left, and 30 key "3" upon the right of the mechanism shown in Fig. 4. This simultaneous delivery of a plurality of tickets, as will be explained technically and in detail, is unattainable with any other mechanism of which 35 I am advised, while filling a need at numerous places.

Each section is rendered potentially and 40 almost instantly operative by means of duplicated ratchet-toothed gears b' mounted upon shaft b , respectively opposing the mutilated ratchet-toothed gears b'' individually actuating shaft c of the corresponding section, when thrown into mesh with gear b' . This latter is afforded a slight relative movement 45 at the end of arm b^3 which is spring actuated below its pivotal shaft b^4 against the stop b^5 . This flexible mounting affords sufficient play to obtain meshing engagement between the gears b' , b'' , when the latter is 50 slightly rotated out of the inoperative position shown in Fig. 5.

Driven shaft c mounts the controlling cam c' , approximately of triangular form from one rounded corner thereof. Adjacent to 55 said cam is the escapement-like member d , which is adapted to initiate the rotation of shaft c and to check it, in co-operation with other means to be described, upon the completion of one revolution. This will occur 60 with the depression of any ticket key, 1, 2, 3, 4 or 5.

These keys, necessarily, are alternatively operated, and reference may be made to Figs. 5 and 6 for explaining their interrelation. 65 These are arranged in banks of any desired

number, but semi-decimal relation of five such keys is most common and desirable from practical and mechanical considerations. The stems $1'$, $2'$, etc. are provided with lateral shoulders $1''$, $2''$, etc., in normal alinement 70 immediately above the common spring detent e pivoted at e' and inwardly actuated by coiled spring e'' . The terminals 1^* , 2^* , etc. of said keys are presented toward the pivoted actuating plate f , having an extension f' bearing upon the top of the master-key g , opposite the pivotal mounting f'' . 75

It will be observed that the shoulder $2''$ is engaged by detent e , Fig. 6, since it is assumed that key 2 was last depressed, hence 80 its terminal 2^* is in a depressed position below the other terminals. In order to release the key last depressed, its shoulder as $1''$, $2''$, etc. will be disengaged by the detent just as the shoulder of the key next depressed passes 85 beyond and outwardly actuates the detent, so that normally only one key is held in the depressed position indicated for key 2. However, in order to release the keys, if accidentally depressed in common and retained by the detent, I have provided the releasing link e^3 , extending exteriorly of the casing h and connected intermediately of said detent. Upon retracting this link and actuating the detent against its spring, any depressed key or keys may manually be restored by their individual springs h' provided therefor in the mounting h'' .

When any key, as 2, is depressed, its shoulder first actuates the detent e and the key last depressed automatically is restored to normal position, while its terminal 2^* depresses the actuating plate f and its extension f' bearing upon master-key g . The function of this member may best be understood by referring to Figs. 6, 7 and 11, which show it in its detaining position, but the dotted line position, Fig. 11, discloses the starting function of the master-key. Thus, the terminal g' , angularly extending from the master-key, first releases the arm of escapement member d' , and the bottom g'' of said master-key engages and initiates the rotation of escapement member d'' mounted on shaft c , as the master-key is 100 fully depressed to the dotted line position, Fig. 11.

The partial rotation of shaft c immediately rotates mutilated gear b'' , turning in a clockwise direction, into meshing engagement with the normally rotated driving gear b' and one complete revolution of shaft c and the members mounted thereon will occur. Thereby cam c' is rotated beneath the roller i' of bell-crank lever i which is pivoted upon the shaft i'' , relaxing the tension of spring i^3 . At the upper end of said lever i there is provided a toothed arm i^4 upon the right and an angularly extending stop i^5 upon the left of the arc shaped terminal i^6 . The path of movement of the stop i^5 is beneath the cut- 110 115 120 125

away portions of the key stems to the left of their actuating terminals 1*, 2*, etc. However, the lower shouldered portion, as 2^a, Fig. 6, of any key in its depressed position will normally extend into the path of stop i^b. Consequently, as member i swings sharply toward the right when released by cam c', the stop i^b will be arrested by key 2 through its depressed shouldered portion 2^a.

As the arc i^a is swung toward the right with member i, the gear k' upon shaft j of the ticket feeding mechanism at the right, will turn the pinion k'' backward through an arc represented by six of the gear teeth, together with the pawl k³, coacting with the five-toothed ratchet k, mounted to rotate shaft j. Assuming the depression of key 2, the movement of these parts will be checked by its shouldered portion 2^a when engaged by the stop i^b, although the plane face of the rotating cam c' otherwise would permit the complete swing of member i toward the right.

Referring for a moment to Fig. 9, it will be seen that in addition to the sleeved gear k'', its controlled pawl k³ and the coacting ratchet wheel k, mounted to rotate shaft j, there are also mounted upon and rotated by said shaft intermittently, the ticket-delivery roll j' having peripheral ribs j'', of which there are five, the counter-gear j³ and the detent-ratchet j⁴, having five faces to correspond with the operative positions of the ratchet wheel k and the ticket-delivery roll j'. Counter-gear or pinion j³ is connected by a driving chain m' to actuate the counter-mechanism m, the ratio being two to one for accommodating the mechanism to decimal actuation of the counter. There is associated with the detent-ratchet j⁴, a spring-pressed arm j⁵ adapted slightly to retard the rotation of shaft j and prevent its reverse actuation, as will be noted from Fig. 5.

The ticket strip n, Fig. 12, is provided with oblong openings n' spaced the distance spanned by the adjacent ribs j'' on the ticket-delivery roll j', so that accuracy in delivering the required number of ticket coupons therefrom is positively insured. A roll or coiled length of this ticket strip having been placed in the receptacle n'', the end of said strip is inserted in the guide n³ and adjusted upon the roll j' so that the openings will register with the ribs j''; said roll being turned until the end of the ticket lies against the depressed blade o of the cutting mechanism at the lower portion of the delivery chute n⁴.

Reverting now to the operation of the ticket-delivery mechanism, it may be assumed that the controlling cam c' has been rotated so that its plane face c'' has passed beneath the terminal roller i' and its curved face c³ is brought into engagement with the roller to effect the reverse movement of member i and

its associated parts against the tensioning spring. Thereby, the toothed arc i^a is actuated toward the left from its detained position corresponding to key 2 and pawl k³, which has slightly overthrown the second tooth, as compared with its normal dotted line position, Fig. 5, will pick up the ratchet k and advance it, together with the members mounted upon actuated shaft j, through an arc corresponding to two of the ratchet teeth, while the delivery roll j' will be correspondingly advanced to extend two ticket coupons beyond the cutting mechanism.

As best shown in Fig. 1, there is provided a spring-pressed member c⁴ lightly tensioned to bear upon the plane face of the co-acting cam upon shaft c when the parts are in normal position ready to be actuated as above described. This light pressure serves to bring the shaft and the members thereon to rest after each rotation, in the starting or full-line position of Fig. 5, from which certain parts are omitted for the purpose of more clearly indicating the essential features. This member, in addition, serves to reposition shaft c and the parts thereon, in the event that a key is held in its fully depressed position by the operator, and member d'' (Fig. 11) first engages the depressed terminal g³ of the master-key in abnormal stopping position, lacking a few degrees rotation to complete the cycle, as previously explained.

Meantime, the cutting blade o has been elevated to permit the extension of the ticket strip n into the delivery chute n⁴ past the severing position, through the action of spring o², when released by the cam o'' acting against the pivoted arm o³ and through the ball-bearing link o⁴, as will be apparent upon referring to Fig. 1. The cutting blade o is centrally notched to clear the delivery roll j', as shown in Fig. 10, and it is pivoted upon the right at o⁵ to insure a shearing action of its edge when depressed from the dotted line position against the ticket strip n and cutting edge o⁶, to the full line position, by the link o⁴. This is effected by the concurrent rotation of cam o'' with cam c' during the period of engagement of its curved face c⁴ with roller i', giving a sufficient interval for a shearing cut, when two ticket coupons will be detached within the chute n⁴, under the conditions assumed, in position to be withdrawn by the purchaser. The counter, meantime, has registered the sale of two tickets, and the mechanism has been restored to its initial condition shown in full line position in the drawings.

In order to provide positive checking means upon the completion of one rotation of shaft c, the escapement-like mechanism affords two alternative stopping positions. Thus, upon referring to Fig. 11, it will be seen that if the key is held in its fully depressed, or dotted line position, member d'' will be

rotated against the side thereof just as the mutilated section of gear b'' is disengaged from the actuating gear b' . If the key has been released, however, the angular terminal gear g' is in position to engage member d' , as shown by full lines, whereby, in either case, the shaft c , with its attached members, is checked after one complete rotation, with the mechanism ready to be operated immediately another key is depressed by the ticket seller.

While normally the motor a'' , Fig. 2, is continuously operated to drive shaft b' extending through any desired number of ticket delivering sections, frequently there are intervals during which no tickets will be sold. During such intervals, the controlling switch h may be left open, if desired, to avoid the slight expense for current and unnecessary wear of the mechanism. In order to start the motor, immediately a line of customers forms at the ticket selling window, a foot-lever of switch h' may be depressed by the ticket seller for the purpose of switching the motor into circuit and rendering all of the sections potentially operative.

Although said sections more commonly will be manned by a single operator or ticket seller for each group, in order to deliver concurrently and with extreme rapidity, varying requirements of ticket sales, it is possible for two or more ticket sellers to be stationed at a group of my improved ticket delivery sections for independently selling tickets therefrom. This is entirely practicable because of the fact that the sections may be independently actuated as well as in any desired groupings, without any possible interference or disablement of the mechanism. In any case, the sequence of ticket deliveries is as rapid and accurate as the ticket seller or sellers are capable of effecting. Normally, one complete cycle may be completed by each section within the interval of one second after a key is fully depressed. Of course, this is more rapid operation than can be accommodated at the ticket selling window.

I may now refer to some structural features and practical considerations in further explanation of my invention. Thus, referring again to Fig. 5, it may be explained that the ratchet-toothed gears b' , b'' , preferably are made from molybdenum-steel and the pitch of the teeth upon the former is greater than that of the latter in order to facilitate the meshing of these gears immediately upon the starting of the latter by the actuation of the master-key. The slightly flexible mounting of the former contributes to this result so that the gears operate smoothly.

It is important to observe that my improved mechanism, while capable of extremely rapid and accurate operation, does not depend upon minutely accurate construction or clearances that are subject to impairment by wear and

use. Instead, the interaction of the different members in succession is accomplished without possibility of mechanical error, with the expenditure of minimum power, with minimum wear, and certainty of operation. The depression of a plurality of keys, for example, will cause merely the delivery and registry of the minimum number of tickets. This results from the fact that the delivery movement is accomplished by the backward actuation of the mechanism intermediately of the master-key and the delivery shaft, which concurrently restores the members to their initial position. I consider this an important and distinctive feature of my invention.

The master-key, in association with the escapement-like members upon the driven shaft, serves in common any desired number of the plurality of operator's keys required for the delivery of a ticket strip with the corresponding number of coupons, and starts and stops the driven shaft upon the completion of one rotation. This, once initiated, is entirely independent of any depressed key, so that the speed of the mechanism is not impaired by the delayed release of any key, while it is impossible, as already explained, for a duplicate delivery to occur.

The operator, merely by glancing at the depressed key which is held in that position until the next key is depressed and then is automatically released, is afforded a visible check upon the instant sale of tickets, or group of tickets, so that the correct payment and change may be verified, or a mistake may be detected and corrected.

Brief reference may here be made to the novel form of severing mechanism, well shown in Fig. 10, and to the unique type of ticket strip shown in Fig. 12. It will be observed that the elongated openings in said strip are positioned transversely thereof so as to minimize the length of cut, while preserving the smooth and continuous outer edges of the strip. Said openings preferably are of short dimension, measured lengthwise of the continuous strip, and serve to separate the ticket coupons partially, as well as to fit upon the ribbed ticket-delivery roll.

To insure an easy shearing cut for the severing mechanism, so that minimum power is required for the gradual operation of the cutter blade, that member is pivoted at a distance upon the right of the ticket strip and it is provided with two cutting sections upon each side of the recess spanning the delivery roll. This entails an arclike movement of the two-section blade, and the elongated opening transversely of the ticket strip, being of greater width than the notch in the cutter blade, affords a previously severed portion into which the transverse cuts of the pivoted two-section blade will merge as it is rotated past the stationary cutting edge.

Having now described the preferred em-

bodiment of my invention and the typical operation thereof by way of explaining the principles and utility, I claim as new, and desire to secure by Letters Patent, together with such modifications as may be made by those ordinarily skilled in the art, the following:

1. In ticket issuing mechanism, the combination with manually-operable movement limiting means for the ticket issuing mechanism, of an associated master-key controlled by said limiting means and adapted to start and stop the actuating means, ticket issuing and severing mechanism, and interposed actuating means for said mechanism, whereby ticket strips of selected lengths may be successively delivered.

2. In ticket issuing mechanism, the combination with manually-operable movement limiting means for the ticket issuing mechanism having variable controlling positions, of an associated master-key controlled by said limiting means and adapted to start and stop the actuating means, ticket issuing and severing mechanism, and interposed actuating means for said mechanism, rendered operative after control by said limiting means, whereby ticket strips of variable lengths may be successively delivered.

3. In ticket issuing mechanism, the combination with manually-operable movement limiting means for the ticket issuing mechanism having variable controlling positions, of an associated master-key controlled by said limiting means and adapted to start and stop the actuating means, a normally driven member, ticket issuing and severing mechanism adapted to be intermittently actuated thereby, and interposed actuating means for said mechanism controlled by said master-key and the limiting means, adapted operatively to connect the driven member and said mechanism, whereby ticket strips of variable lengths may be successively delivered.

4. In ticket issuing mechanism, the combination with manually-operable movement limiting means for the ticket issuing mechanism having variable controlling positions, of an associated master-key controlled by said limiting means and adapted to start and stop the actuating means, a normally driven member, ticket issuing and severing mechanism adapted to be intermittently actuated thereby and rendered operative after control by said limiting means, and interposed actuating means for said mechanism controlled by said master-key adapted operatively to connect the driven member and said mechanism and to disconnect them after one complete cycle.

5. In ticket issuing mechanism, the combination with a plurality of manually-operable movement limiting keys for the ticket issuing mechanism, of an associated master-key, a normally driven member, ticket issu-

ing and severing mechanism, and interposed actuating means for said mechanism, including an intermittently driven member, a controlling cam and an escapement actuated by the master-key to start and stop the operation after one complete cycle.

6. In ticket issuing mechanism, the combination with a plurality of manually-operable movement limiting keys for the ticket issuing mechanism, of individual detent mechanism therefor, a master-key associated with the group of limiting keys, a normally driven member, ticket issuing and severing mechanism rendered operative only after control by one of the limiting keys, and interposed actuating means for said mechanism, including an intermittently co-acting driven member, a controlling cam and an escapement actuated by the master-key to start and check operative connection after one complete cycle.

7. In ticket issuing mechanism, the combination with manually-operable movement limiting means for the ticket issuing mechanism having variable controlling positions, of an associated master-key controlled by said limiting means and adapted to start and stop the actuating means alternatively actuated from any controlling position, ticket issuing mechanism, actuating means for said mechanism including a driving member, and means interposed between said master-key and controlled thereby for intermittently connecting said ticket issuing mechanism with the driving mechanism and for disconnecting them after one complete cycle.

8. In ticket issuing mechanism, the combination with a set of alternatively operable movement limiting keys for the ticket issuing mechanism, of an associated master-key, ticket issuing mechanism, a normally driven member, and actuating means for said mechanism interposed between said mechanism and the master-key, including an intermittently co-acting driven member, a controlling cam and escapement, adapted to be started and stopped after one complete cycle, as regulated by any limiting key.

9. In mechanism of the class described, the combination with a normally driven gear, of a co-acting mutilated gear, an associated escapement, and a controlling key acting upon said escapement adapted to mesh the mutilated gear with the driven gear and to check its rotation after one complete cycle.

10. In mechanism of the class described, the combination with manually-operable limiting means, of an associated master-key, a normally driven gear and a co-acting mutilated gear normally at rest, and an escapement mechanism interposed between the latter and said master-key adapted to effect the operative engagement of said gears for one complete cycle, and ticket issuing mechanism concurrently actuated thereby and controlled by said limiting means.

11. In mechanism of the class described, the combination with a normally driven gear and its co-acting mutilated driving gear respectively of different pitch, of a controlling key, and associated escapement mechanism normally checking said driving gear after each revolution, but positioned to effect the meshing of said gears with each actuation of the controlling key.
12. In mechanism of the class described, the combination with a ticket-delivery roll, of ratchet mechanism connected to actuate said roll in one direction, and a pinion mounted to rotate with the ratchet, a driving member engaging said pinion, and manually-operable movement limiting means adapted variably to control the movement of said member.
13. In mechanism of the class described, the combination with a rotatable delivery-member, ratchet mechanism connected to actuate to said roll in one direction, and a pinion associated therewith for its actuation, of a movable gear rotating said pinion, and manually-operable movement limiting means adapted to regulate the amplitude of the operative movement of said delivery-member whereby the delivery-member may be variably actuated.
14. In mechanism of the class described, the combination with a rotatable delivery-member, ratchet mechanism and a pinion associated therewith for its actuation, of a movable gear rotating said pinion, a set of alternatively operated limiting keys adapted variably to control the movement of the gear, and means for actuating the delivery-member upon the reverse movement of said gear after limitation thereof by any key.
15. In mechanism of the class described, the combination with a plurality of ticket-issuing appliances, each comprising a set of movement-limiting keys for the ticket delivery mechanism, and independently controlled delivery and severing mechanisms for the tickets of different classes, actuating means for said mechanism interposed respectively between said keys and said mechanisms, and a common motor device adapted to be concurrently connected for the independent operation of a plurality of such ticket-issuing appliances.
16. In ticket delivery mechanism, the combination with a plurality of manually-operable movement-limiting keys for the ticket-delivery mechanism, of individual detent mechanism for the group of keys, a master-key operatively associated with said group, a normally driven gear, ticket-delivery mechanism rendered operative only after control by one of the limiting keys, and interposed actuating means for said mechanism, including a co-acting mutilated gear, a controlling cam respectively for the delivery mechanism and the master-key, whereby the latter is adapted to start and stop the actuating means in cyclic relation upon the complete limiting movement of any manually-operable key.
17. In mechanism of the class described, the combination with ticket-delivery means, of ratchet mechanism connected to actuate the latter in one direction, a pinion mounted upon its shaft, a driving member engaging said pinion having a backward and forward movement, and manually-operable limiting means adapted variably to control the amplitude of movement of said driving member.
18. In mechanism of the class described, the combination with a ticket-delivery member of materially less width than the ticket strip, of associated cutting blades positioned on either side thereof, and a movable coacting cutting blade bridging said ticket-delivery member in its cutting position.
19. In mechanism of the class described, the combination with a set of ticket-issuing keys, of a normally driven gear, a coacting mutilated gear, and a master-key common to the set of ticket-issuing keys connected to actuate the mutilated gear into operative relation with the driven gear.
20. In mechanism of the class described, the combination with a driven gear, of a coacting mutilated gear, and a controlling master-key connected to impart an initial impulse to the mutilated gear, and to check its rotation after one complete cycle.
- In testimony whereof I do now affix my signature.
- LOUIS SCHER.
